UNITED STATES PATENT OFFICE.

EDWARD J. SHEA, OF BROOKLYN, NEW YORK.

EARRING SAFETY GUARD.

Application filed October 25, 1924. Serial No. 745,891.

To all whom it may concern:

Be it known that I, EDWARD J. SHEA, a citizen of the United States, residing at 322 Carlton Avenue, borough of Brooklyn, in the county of Kings, city and State of New York, have invented a new and useful Earring Safety Guard, of which the following is a specification.

The invention relates to improvements in a safety earring guard made from metal or fibre; the object of the improvement is to support an earring while hung in the lobe of the ear where the ear has been pierced for that purpose, and also to support ear rings applied by the use of a fastener which extends through the lobe of the ear or around the same.

The improvement is designed to relieve painful and sore ears frequently caused by the weight of a hanging earring, and ear rings fastened to the ear by screw pressure which stops the circulation of the blood.

The form of the invention is illustrated in the accompanying drawing, in which Figure 1, is a side view of the guard; Figure 2, is a view of the back edge of the guard.

The hook or hanger A. D. acts as a support when placed behind the back and over the top of the ear; sustains the strain or weight of the earring, holds it in position, prevents it from dropping and guards it against loss.

The thumb piece B, is for the purpose of placing the guard in position when attached or un-attached to the earring and prevents it from turning while hung.

The spring hook has a flat surface on both

sides and fits against the lobe of the ear, supports the wire or bar of the earring which passes through it; with the slightest screw pressure the earring is held in place without stopping the circulation of the blood.

The hook C terminates in a ball E which will be disposed between the lobe of the ear and the head at the juncture between the lobe of the ear and the head and will prevent the guard from riding up, the lobe of the ear being brought against the flat portions of the hook C when the earring is applied.

I claim:

1. An article of the class described, comprising a hanger for suspending the article from an ear, and a hook substantially flat to provide comparatively wide portions which lie against the lobe of the ear, the hook being in the plane of the hanger and serving for receiving a portion of an earring to support the earring.

2. An article of the class described formed from a single piece of material to provide a hanger for suspending the article from an ear, a hook substantially flat to provide comparatively wide portions which will lie against the lobe of the ear, the hook further serving for receiving a portion of an earring to support the earring, and a comparatively wide grasping portion in the plane of the hanger to facilitate the application of the article to the ear and to give stability to the article when applied.

EDWARD J. SHEA.
